VACUUM CLEANER

Tord Erik Daniel Bilde, Stockholm, Sweden, assignor to Electrolux Corporation, Dover, Del., a corporation of Delaware

Application December 15, 1932, Serial No. 647,345
In Germany June 16, 1932

7 Claims. (Cl. 116—114)

My invention relates to vacuum cleaners and the object is to provide a device for indicating the condition of the dust separating member.

The invention will be apparent from the following description considered in connection with the accompanying drawing, which forms a part of this specification, and of which:

Fig. 1 is a cross-sectional view of a vacuum cleaner embodying my invention in preferred form;

10 Fig. 2 is a cross-sectional view on an enlarged scale of a portion of the device shown in Fig. 1; and

Fig. 3 is an elevational view of the portion shown in Fig. 2, looking from the left in Fig. 2.

15 Referring to the drawing, reference character 10 designates a container constituting the lower portion of a dust receiver. The container is preferably cylindrical and made of rigid impervious material, such as sheet metal. The upper part of container 10 is formed with an outwardly extending flange 11 and an upwardly extending rim 12. An air inlet connection 13 is made integral with or secured to the side of container 10 approximately half way between the top and bottom of the member. A flexible hose 14 is adapted to be secured to connection 13. The hose leads from any suitable cleaning implement 15.

20 The top of the dust receiver comprises an annular ring 16 provided with a packing 17. Packing 17 is adapted to rest on flange 11 and to fit snugly within rim 12. The inner edge of ring 16 is formed as a flange 18 to which is secured a dust separating member 19 made of suitable cloth or the like which is pervious with respect 25 to air but prevents the passage therethrough of dust and dirt particles. Dust separating member 19 may be secured to flange 18 by means of a string or cord 20.

25 A circular plate 21 formed with a downwardly extending flange 22 is adapted to be placed on packing 17 and to hold the packing and plate 16 in place. The more central part of plate 21 is formed as the lower wall of a centrifugal fan chamber 23 and is provided with an inlet opening 24 which establishes communication between the space above dust separating member 19 and the fan chamber. A member 25 constitutes the upper wall of the fan chamber and serves as a support for an ordinary electric motor 26, which is suitably secured thereto. The armature shaft 27 of the electric motor carries a rotor 28, which rotates within fan chamber 23. Member 25 is provided with a more or less central opening 29 through which extends shaft 27. The motor is

30 enclosed in a casing 30. A convolute 40, formed by members 21 and 25 serves as an exhaust conduit for the fan and opens to the atmosphere.

Member 10 is provided with an air-tight window 31 situated above inlet connection 13. Arranged within member 10 adjacent to window 31 is a box-like structure 32 formed with a slot 33 in the lower part thereof. A spindle 34 is supported within box-like structure 32. A signal 35 is rotatably mounted on spindle 34. Signal 35 comprises a bell crank lever, one arm 36 of which is provided 35 with a disc or like member 37 which is distinctively marked, either by being colored or by bearing a legend. The other arm 38 of the bell crank lever extends through slot 33 and is provided with a vane 39 disposed in front of the inlet opening 13. Signal 35 is so balanced that, when free from outside influences, it is in the position shown in full lines in Fig. 2, that is, with plate 37 visible through window 31 and arm 38 in a substantially vertical position.

25 In operation, rotation of the fan rotor 28 causes air to be drawn in through implement 15, hose 14 and inlet connection 13 into the interior of casing 10. If the implement 15 is passed over a dusty surface, dust and dirt will be drawn in with this air. The air entering through inlet connection 13 has a comparatively high velocity and is directed against vane 39 and causes the bell crank lever 36 to be rotated in a counter-clockwise direction about spindle 34. This causes disc 37 to take the position shown in dot-and-dash lines in Fig. 2, whereby the distinctive coloring or legend carried by the disc is not visible through the window 31.

30 The velocity of the air is reduced when it enters dust receiver 10 and much of the dust is deposited in the bottom of the receiver. However, some of the dust passes along with the air upwardly through the receiver and is stopped by the dust separating member 19, while the air passes through the member and through opening 24 into the fan chamber. The air is discharged from the fan chamber through the convolute 40 to a suitable discharge opening.

35 After the vacuum cleaner has been operated for a greater or lesser length of time, sufficient dust accumulates in the receiver so that much dust is at all times in agitation therein and is drawn up against the dust separating member 19. This interferes with the passage of air through the dust separating member and this increase in the resistance to flow of air reduces the velocity with which the air is drawn into the receiver through the inlet connection 13. This in 40 45 50 55

turn reduces the force exerted by the air against vane 39 and the arm 38 tends to take a more vertical position, thereby rotating plate 37 upwardly so as to be visible through the window 31. As before pointed out, this plate may be brightly colored or bear a legend such as the word "Full". When the operator perceives the indication mark through the window 31, it indicates to him that sufficient dust has accumulated within the receiver so that it should be emptied.

In order to empty the dust from receiver 10 it is only necessary to remove the motor and fan assembly, whereupon ring 16 and dust separating member 19 may be lifted off the lower portion. The lower member may then be turned over and the dust deposited in any suitable place. It is also advisable to shake the dust separating member 19 and tap the upper side of it to dislodge any dirt adhering to the lower side.

While I have shown and described one specific embodiment of my invention, it is to be understood that this is for the purpose of illustration only and that many modifications thereof fall within its scope, which is to be determined by the appended claims viewed in the light of the prior art. It will be obvious that my novel indicator is applicable to other types of vacuum cleaners than that disclosed.

What I claim is:

1. The combination with a vacuum cleaner comprising a casing forming a dust receiver having an air inlet opening and a pervious dust separating member and means for producing flow of air through said receiver, of a signal, and means for operating said signal comprising a member pivoted within said casing, one end of the pivoted member being adjacent to said inlet opening so as to be in the path of air passing therethrough whereby said pivoted member is adapted to be moved by the current of air.

2. The combination with a vacuum cleaner comprising a dust receiver having an air inlet opening and a pervious dust separating member and means for producing flow of air through said receiver, of means for indicating the condition of said dust separating member comprising an air-tight window in said receiver, and a signal pivoted within said receiver, one end of said signal being provided with a vane disposed adjacent to said inlet opening so as to be in the path of air passing therethrough and the other end of said signal being disposed so as to be visible through said window.

3. The combination with a vacuum cleaner comprising a dust receiver having an air inlet opening and a pervious dust separating member and means for producing flow of air through said receiver, of means for indicating the condition of said dust separating member comprising an air-tight window in said receiver, and a signal pivoted within said receiver, one end of said signal being

disposed adjacent to said inlet opening so as to be in the path of air passing therethrough and the other end of said signal being provided with a distinctively marked plate disposed so as to be visible through said window.

4. The combination with a vacuum cleaner comprising a dust receiver having an air inlet opening and a pervious dust separating member and means for producing flow of air through said receiver, of means for indicating the condition of said dust separating member comprising an air-tight window in said receiver, and a signal pivoted within said receiver, one end of said signal being provided with a vane disposed adjacent to said inlet opening so as to be in the path of air passing therethrough and the other end of said signal being provided with a distinctively marked plate disposed so as to be visible through said window.

5. The combination with a vacuum cleaner comprising a dust receiver having an air inlet opening and a pervious dust separating member and means for producing flow of air through said receiver, of means for indicating the condition of said dust separating member comprising a box-like structure secured to the side of said receiver, an air-tight window in said receiver arranged to make visible the interior of said structure, a signal pivoted within said structure and having two arms, the bottom of said structure being formed with a slot and one of said arms extending through said slot, a vane secured to the end of said one arm and disposed adjacent to said inlet opening so as to be in the path of air passing therethrough, and a distinctively marked plate carried by the other of said arms within said structure so as to be visible through said window.

6. The combination with a vacuum cleaner comprising a casing forming a dust receiver having an air inlet and a pervious dust separating member and means for producing flow of air through said casing, of means for indicating the condition of said dust separating member comprising an air-tight window in said casing, and a signal pivoted within said casing, one end of said signal comprising a vane disposed so as to be in the path of air passing through said casing and the other end of said signal being disposed so as to be visible through said window.

7. The combination with a vacuum cleaner including a casing having an air inlet opening, a pervious dust separating member and means for producing flow of air through said casing and through said dust separating member, of a signal and means for operating said signal including a member pivoted within said casing, one end of the pivoted member being disposed in the path of air passing through said casing whereby said pivoted member is adapted to be moved by the current of air.

TORD ERIK DANIEL BILDE.
